United States Patent Office

Des. 176,926
Patented Feb. 14, 1956

176,926

REGISTER

Wilbert J. Parrish, Battle Creek, Mich., assignor to United States Register Company, Battle Creek, Mich., a corporation of Michigan

Application September 27, 1954, Serial No. 32,439

Term of patent 14 years

(Cl. D81—21)

— FIG. 2 —

Figure 3 is an end view of the register, the opposite end having the same general appearance.

I claim:

The ornamental design for a register, substantially as shown and described.
